United States Patent Office.

ALBERT E. KRÖGER, OF NORWALK, CONNECTICUT.

Letters Patent No. 102,557, dated May 3, 1870.

IMPROVED SHOE-FASTENING.

The Schedule referred to in these Letters Patent and making part of the same.

To all whom it may concern:

Be it known that I, ALBERT E. KRÖGER, of the town of Norwalk, county of Fairfield and State of Connecticut, have invented certain new and useful Improvements in Boots and Shoes, of which the following is a specification.

Nature and Object.

My invention consists in the arrangement of an improved mode of fastening the open parts of boots and shoes by means of metallic sliding and slotted plates, which are attached to a movable front piece or tongue, and studs fastened to the edges of the open part of the upper, to be used in the place of laces or buckles.

The Drawing Accompanying this Specification.

Figure 1 is a view of a ladies' boot, showing the tongue and plates as they appear when fastened. This is a front view, but the same arrangement answers equally well when used on the side of the boot.

The boots and shoes are made in the usual manner, open at the front or side.

The thin plates of metal B C are stamped out to any required pattern, either plain or ornamental, and are attached to the front piece or outer tongue A.

The plate B has a long slot, D, extending from end to end, for the studs E to slide in.

The plate C has the same kind of slot D, but with an additional cross-slot, F, at the upper end, for the admission of the heads of the T-studs E, in a similar manner as a button passes through a button-hole, the shank of the stud being of the same size as the opening of the long slot D, so that it will slide along freely in the same.

Both plates, B and C, are permanently attached to the movable front piece or tongue A, by means of

eyelets, or other suitable device, passing through the edge of the open loose part of the boot, and a thin piece of whalebone, or other elastic suitable material, which is placed on the edge and sewed between the leathers. This is to give a stiffening to the edges, and prevent them from crinkling or tearing, and allow the studs to work up and down with freedom.

On the upper corners of the edges of the open part are small hooks to hook into eyelets I I, to hold up and retain in its place the front piece or tongue A, when fastened, and prevent its sliding downward.

The front piece or tongue A is made independent of the boot, and is held in position by the studs E, being first passed in through the long slot in the plate B, and fastened to the edge of the boot, the other edge remaining free, with the studs in opposite, till the boot is on the foot. The stud-heads E are then passed through the cross-slots in the same way as a button, then the front is pulled upward, and the studs slide in the slots, and the upper end is hooked on the hooks I I to hold it up, and the whole fastening is completed in a neat and permanent manner.

To unfasten the same, unhook the top from the hooks and eyelets I I, then push downward the front piece, and the studs will slide up to the cross-slots in the plate C, and the heads will pass through to relieve all.

What I claim as my invention is—

The arrangement of the front piece or tongue A with the slotted metallic plates B and C, and the studs E, in the manner substantially as herein set forth, and for the purpose described.

A. E. KRÖGER.
